ALBERT E. HUTT, OF NEW ROCHELLE, NEW YORK

PRESSURE DEVICE IN DISPENSING FLUIDS AND SEMIFLUIDS

Application filed October 1, 1929. Serial No. 396,457.

My invention, generally stated, relates to a novel pressure device used in dispensing fluids and semi-fluids from their original containers and is designed to accommodate a can, keg, barrel or the like containing a fluid or semi-fluid, such as oil, grease, or the like, as usually sold in such manner that when pressure is raised within the chamber of the device it will be exerted alike upon 10 the outside as well as upon the inside of such container, so that while the contents of the container will be forced to the outside of the pressure chamber through a pipe provided for that purpose, the container itself will 15 not have to withstand the destructive force of said pressure as it would have to do if the pressure were introduced on the inside of such container only.

My invention further relates to a device 20 having a pressure chamber so arranged and constructed that it may accommodate a plurality of containers.

My invention further relates to a device having a pressure chamber so arranged and 25 constructed that it may be hermetically sealed and also be provided with means for raising pressure within the same to a point above the pressure of the surrounding atmosphere.

30 My invention still further relates to the provision of means for indicating pressure raised within the chamber of the device and also relates to the provision of a safety device to prevent such pressure becoming 35 greater than that for which the chamber is constructed.

My invention still further relates to means for drawing off any water that may accumulate in the chamber of the device due to 40 condensation, for example.

The invention consists of the novel construction hereinafter described and finally claimed.

For the purpose of illustrating my invention I have shown in the accompanying drawings two forms thereof which are at 45 present preferred by me, since the same have been found in practice to give satisfactory and reliable results, although it is to be understood that the various instrumentalities

of which my invention consists can be variously arranged and organized and that my invention is not limited to the precise arrangement and organization of the instrumentalities as herein shown and described. 55

The nature, characteristic features, and scope of the invention will be more fully understood from the following description taken in connection with the accompanying drawings forming part hereof, and in which: 60

Fig. 1, represents a view in central section of a device embodying my invention.

Fig. 2 represents a plan view of the top of the pressure chamber showing the lugs which are designed to engage similar lugs on base 65 plate of the chamber.

Fig. 3 represents an enlarged plan view of the base and lugs shown in Fig. 1.

Fig. 4 represents a fragmentary view in central section of my novel pressure chamber 70 upon an enlarged scale.

Fig. 5 represents in vertical section a detail of the check valve construction herein-after referred to.

Fig. 6 represents a view in vertical section 75 of a modified form of construction.

Fig. 7 represents a sectional plan view of Fig. 6.

Fig. 8 represents in vertical section a detail hereinafter referred to. 80

Referring now to the drawings in detail, and especially to Figs. 1, 2, 3, and 4, the reference numeral 1 designates the pressure chamber of my novel device and comprises a generally cylindrical member having an 85 integral dome-shaped upper part 2 and a separate base 3. The reference numeral 4 designates the retaining lugs upon the dome shaped upper part 2, and 5 designates similar lugs on the separate base 3. 6 designates 90 a turn table in the base 3 to facilitate moving of the barrel when the lugs 4 are engaged with the lugs 5. 7 designates a circular seal of flexible material, preferably rubber, which seals the joint between the casing 1 and the base 3. The higher the pressure raised in the chamber 1 the tighter the seal is maintained between the sealing parts. 8 designates a metal drum or container having a 95 regular opening 9 through which passes 100

loosely a telescopically arranged pipe 10 which is fastened to the top of the dome-shaped upper part 2 of the chamber 1. Any number of drums 8 may be employed. 11 is a pipe arranged upon the outside of dome 2, and is connected with the pipes 10 for the purpose of drawing off the contents of the drums 8 when pressure is applied inside the chamber. 12 are handles on the outside of the casing 1, for the purpose of turning the same to engage the lugs 4 with the lugs 5. 13 designates a pressure relief valve. 14 designates a pressure indicating gauge and 15 indicates a check valve through which compressed air is introduced into the casing 1.

Referring now to Fig. 6, the casing 1 comprising the pressure chamber is shown as buried beneath flooring 16 of a building. 17 designates a cover to close the opening 18 beneath it, which opening is for the purpose of lowering the drums 8 into the interior of casing 1. 19 is a pipe leading to the pressure relief valve to be placed at any suitable place above the floor. 20 is a pipe leading to the pressure gauge also placed above the floor, and 21 is a pipe leading to the check valve for the introduction of compressed air. 22 is a valve for the purpose of drawing off any water into a sewer by way of pipe 23. The seal 28 in this installation seals the joint between the casing 1, opening 18 and the cover plate 17. 24 represents stuffing boxes to seal the joints in the telescopic pipes 10 and to hold them in a raised position while the drums are placed beneath them or are removed when empty. 25 designates any suitable means for heating which in the present case may be steam coils for the purpose of heating the interior of the chamber if desired. While in Fig. 6 I have illustrated the heating means as being applied to the device as shown, it will be understood that suitable heating means may be applied to the device as best seen in Fig. 1.

The operation of both of the devices shown in the above described figures being identical in principle, it is only necessary to refer to Fig. 1.

Referring now to Fig. 1, the drum 8 is placed upon the turntable 6 of the base 3 and the closing plug is removed from the aperture 9 of the drum. The dome-shaped member 2 is then placed over the drum 8 and 55 on the base 3 so that the lugs 5 cooperate with the lugs 4 and the telescopic pipe 10 fits through the aperture 9. The dome-shaped member 2 is then turned by the handles 12 so that the lugs 4 pass under the lugs 5. The drum 8 will have to turn with the dome-shaped member as the pipe 10 passes loosely through the aperture 9 of said drum, whereby the pressure is exerted directly upon the contents of said drum or 60 container. The seal 7 is fixed, in any suit-

able manner, to the dome-shaped member to facilitate handling. Compressed air is then introduced through the check valve 15 until the desired pressure is reached within the casing 1, as will be indicated by the gauge 14. The pressure of air acting upon the seal 7 will close the casing 1 hermetically. As the pipe 10 has a loose fit with the aperture 9 the pressure in the casing 1 will be evenly distributed both inside and outside of the drum 8 and directly on the contents of the latter so that there is no tendency for the drum to break open. The pressure of air, however, acting upon the contents of the drum 8 will force the contents thereof out 80 through the pipes 10 and 11.

The construction shown in Fig. 6 is provided with steam pipes 25 passing around the inside of casing 1 for the purpose of raising the temperature of the contents of the drums 8 to facilitate passage of such contents through the pipes 10 and 11 if they were of a character as to need this assistance, which would be the case with heavy bodied greases and the like.

It will be apparent that with the use of my novel pressure device I am enabled to greatly facilitate the removal of fluids and semi-fluids from comparatively fragile containers with the aid of air pressure, which is quite desirable and, commercially considered, possesses advantageous features.

By the above arrangement, construction and combination of parts I also have provided a relatively inexpensive, simple and efficient pressure device for the removal of fluids and semi-fluids from relatively fragile containers. Another advantage resides in the fact that my novel construction of parts may be employed above ground or beneath ground, as desired.

Referring now to Fig. 5, the same illustrates in central section the air inlet 15 shown at the top of Fig. 1. In this figure the top 2 of casing 1 is shown with an opening 26 to admit air, and the attachment is provided with a spring pressed spherical valve 27.

Referring now to Fig. 8, I have shown in detail the stuffing boxes 24 illustrated in Fig. 6. A stuffing box is provided in each pipe 10 to prevent air leakage from the casing 1, when the contents of drum 8 is below this point. The lower or smaller pipe section which telescopes into the upper or larger pipe section 10 is provided with the parts 29, as seen in Figs. 1 and 8, to permit the ingress of the fluid or liquid which is to be discharged through the outlet pipe 11, which may be provided with a check or other valve 30 if desired. The eye 31 on the dome 2, see Fig. 1, enables the latter to be readily hoisted and lowered into place. It will be understood that the friction between the contiguous surfaces of the telescoping pipes 130

will cause them normally to assume substantially the position seen in Figs. 1 and 8.

It will be apparent from the foregoing that by my invention I am enabled to utilize a standard or conventional lubricant drum or container having a fixed top and by merely removing the plug or closure from the aperture 9 and loosely inserting therein the exit pipe 10, and its adjuncts, a free space is afforded for exerting pressure directly upon the contents of the container through the opening 9, and I am thus enabled to dispense with a follower and a stuffing box thereon as has heretofore been proposed. By my device the lubricant can be readily dispensed from the original container without the use of spoons, paddles, or the like, and the lubricant or other material is at all times protected from the ingress of dirt, dust, or other foreign and deleterious substances. It will be obvious that my invention is equally well adapted for dispensing any other material than lubricants in a fluid, plastic, or semi-plastic condition.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having thus described my invention, what I claim as new, and desire to secure by Letters Patent, is:

1. A device of the character stated comprising a base, a casing detachable from said base and having its lower end hermetically sealed with respect to said base, said casing having a space therein to receive a fluid or semi-fluid container, a container having a fixed top within said casing, an exit pipe fixed in said casing for placing the contents of said container in communication with the outside of said casing, and means for raising the pressure within said casing and inside of said container simultaneously and equally, the pressure so raised being used directly on the contents of said container to expel said contents therefrom.

2. A device of the character stated comprising a base, a casing detachable from said base and having an open bottom, means for closing said open bottom hermetically with respect to said base, said casing having a space for the reception of a fluid or semi-fluid container, an opening in said container to connect the interior of such container with the interior of said casing, pipes passing loosely through said container opening to connect the contents of said container with the outside of said casing, and means for raising the pressure inside of said casing,

the pressure so raised being used directly on the contents of said container to expel said contents therefrom.

3. A device of the character stated comprising a casing having a top and radially disposed lugs at its bottom, a base having radially disposed lugs to co-operatively receive the lugs of said casing, an hermetically tight seal between the bottom of said casing and said base, a turntable arranged at the bottom of said device, a container positioned upon said turntable, a telescopically arranged pipe extended through said top into said container, and means for raising the pressure inside of said casing and container 80 equally and simultaneously.

4. A device of the character stated comprising a casing having a top and radially disposed lugs at its bottom, a base having radially disposed lugs to co-operatively receive the lugs of said casing, an hermetically tight seal between said casing and base, a turntable arranged at the bottom of said device, a container positioned upon said turntable, a telescopically arranged pipe extended through said top into said container, means for raising the pressure inside of said casing and container equally and simultaneously, and handles extended from the upper part of said casing for the purpose of 95 moving said casing about its vertical axis, to cause the interlocking of said lugs.

5. A device of the character stated comprising a cylindrical casing having a top and radially disposed lugs at its bottom, a base having radially disposed lugs to co-operatively receive the lugs of said casing, a turntable arranged at the bottom of said device, a container positioned upon said turntable and having an opening in the top thereof, a telescopically arranged pipe extended loosely through said top into said container, a stuffing box for sealing the joint between the two parts of the telescopic pipe, and means for raising the pressure inside of said casing and container equally and simultaneously, said pressure being exerted directly on the contents of said container to expel them through said telescopic pipe.

6. A device of the character stated comprising an integral casing having an opening in the bottom thereof, a base on which said casing is detachably mounted, means for closing said opening hermetically with respect to said base, said casing having a space for the reception of a fluid or semi-fluid container, an opening in said container to connect the interior of such container with the interior of said casing, pipes to connect the contents of said container with the outside of said casing, and means for raising the pressure inside of said casing.

7. A device of the character stated, comprising a base, an outer casing closed at its top and open at its bottom and its bottom

end engaging said base, an hermetically sealing device common to said casing and said base, a container having a fixed top, side walls and base, an exit pipe loosely passing through said fixed top of said container and extending to nearly the bottom thereof, and means for creating pressure within the space between said casing and container, said pressure passing into said container through the exit pipe opening in the fixed top thereof, and being exerted directly on the contents of said container.

8. A device of the character stated, comprising a base, an outer casing closed at its top and open at its bottom and its bottom end engaging said base, an hermetically sealing device common to said casing and said base, a container having a fixed top, side walls and base, an exit pipe loosely passing through said fixed top of said container and extending to nearly the bottom thereof, means for creating pressure within the space between said casing and said container, said pressure passing into said container through the exit pipe opening in the fixed top thereof and being exerted directly on the contents of said container, and a heating device intermediate said casing and container.

9. A device of the character stated, comprising a base, a turntable on said base, an outer casing having an integral top and pendant continuous wall interlocked at its lower end with said base, an hermetical sealing device common to the lower end of said casing and said base, a container having a fixed top, side walls and a base, the latter being mounted on said turntable, an exit pipe loosely passing through the fixed top of said container and extended to nearly the bottom thereof, and means for introducing fluid pressure into the space between said casing and container and directly into the contents of the latter to expel said contents through said exit pipe.

45 10. A device of the character stated, comprising a base, an outer casing having its lower end hermetically sealed with respect to said base, a turntable on said base, a container seated on said turntable, an exit pipe fixed in said casing and loosely inserted in said container, and means for raising the pressure inside of said casing and container equally and simultaneously, said raised pressure being exerted directly on the contents of said container to expel said contents through said exit pipe.

11. In a device of the character stated, a base, a pressure chamber casing therefor detachably mounted on said base and composed of a top and a pendant annular wall open at its bottom and seated on said base, a hermetical sealing device interposed between said base and the bottom of said pressure chamber casing, an exit pipe secured in the top of said pressure chamber casing and

extending nearly to said base when the latter and said casing are assembled, and an inlet pipe disconnected from said exit pipe and fixed to said top, whereby said top, exit pipe and inlet pipe are movable as a unit with respect to said detachable base.

12. In a device of the character stated, a base, a pressure chamber casing therefor, detachably mounted on said base and composed of a top and a pendant annular wall open at its bottom and seated on said base, a hermetical sealing device interposed between said base and the bottom of said pressure chamber casing, an exit pipe secured in the top of said pressure chamber casing and extending nearly to said base when the latter and said casing are assembled, an inlet pipe disconnected from said exit pipe and fixed to said top, whereby said top, exit pipe and inlet pipe are movable as a unit with respect to said detachable base, and a turntable mounted on said base.
